INTERQUAD CAPACITY BALANCING OF TELEPHONE CABLE CIRCUITS

Application filed December 4, 1928, Serial No. 323,674, and in Germany December 22, 1927.

This invention pertains to capacity balancing between closely paralleling transmission circuits with the object of preventing current impulses transmitted over one such circuit from influencing the other circuit through the medium of capacitative couplings between such circuits. More specifically, the invention discloses a novel scheme applicable principally to quadded 10 telephone cable for balancing the couplings between the transmission circuits of a first and of a second quad in such manner that signals transmitted over the circuits of the one quad will produce no interfering effects 15 upon the circuits of the second quad or vice versa.

The invention in essence consists in measuring the capacitative couplings between the speaking circuits of the first and 20 those of the second quad and, from the coupling values thus obtained, determining directly by means of a mathematical process the values of nine fixed capacities which, when properly connected between suitable 25 conductors of the one and of the other quad in accordance with the coupling equations will cause all the inter-quad couplings between the transmission circuits simultaneously to disappear so that the speaking circuits 30 of the one quad will produce no interfering effects upon the speaking circuits of the other quad.

The invention discloses several novel 35 features as compared to the prior art. With the disclosure of the present invention, only nine capacities are required for balancing up the inter-quad capacitative couplings of the speaking circuits, whereas with methods known to the art a larger number of condensers is required to accomplish this result. A second novel feature lies in the fact that 40 the capacitative couplings are all measured up at one time and, by means of the mathematical procedure outlined, the balancing 45 condensers determined directly, whereas it

has formerly been necessary in balancing up inter-quad capacities to measure and correct the couplings between certain speaking circuits before the coupling between other speaking circuits can be measured and corrected. A third advantage of the scheme disclosed herein consists in the fact that, in 50 balancing up quadded cables on a large scale, a much smaller number of types and sizes of condensers need be kept in stock than was 55 formerly the case.

It is the well known practice in manufacturing cables for use in long distance telephone service, to twist together the lead and return wire constituting each physical circuit. Two such twister pairs are in turn twisted into a quad to constitute the lead and return conductor of the phantom circuit in 60 a phantom group. Each cable contains a number of such quads. The twisting is done 65 in a scientific manner to reduce in so far as possible, the interfering effects between the various talking circuits of the cable which result from the inductive and capacitative 70 couplings between the same. In spite of the precautions taken in this respect, however, there are residual unbalance effects which in some instances become objectionable. The 75 capacitative unbalances of short sections of cable can be offset by suitably connecting fixed capacities between certain conductors of the one and the other groups of speaking circuits.

The interfering effects of the talking circuits of one quad on those of a second quad, due to capacitative couplings between the same, may be viewed in two different ways. In the first place, it may be stated that between the four conductors of one quad and the four conductors of a second quad are located sixteen distinct part capacities. If 80 these capacities are all equal, then the inter-quad couplings are completely balanced, and the circuits of one quad will have no interfering 85 effect on the circuits of the second quad, 90

or vice versa. In accordance with a second view, it may also be stated that each quad contains three speaking circuits, two physical or side circuits and a phantom circuit. Between the three speaking circuits of one quad and the circuits of a second quad, nine couplings arise. In accordance with these two views, it would seem that the mutual influencing of the speaking circuits between quads can be removed in two ways; (1) by establishing complete symmetry between quads, by making sixteen part capacities all equal or (2) by balancing up the nine capacitative couplings between speaking circuits.

In respect to the second view above, it is well known that the capacitative coupling between two speaking circuits can be balanced by appropriate connection of a single condenser between a conductor of one speaking circuit and a suitable conductor of a second speaking circuit. It thus appears possible to remove the nine capacitative couplings between the speaking circuits of a first and a second quad by the proper connection between certain conductors of the first and second quad of only nine suitably chosen capacities. On the other hand, if the first method of balancing mentioned above is decided upon then fifteen condensers are required for balancing purposes, i. e., fifteen additions which make all the smaller part capacities equal to the greatest.

Now, the present invention starts from the conception of removing the nine capacitative couplings by the method of connecting only nine condensers between the conductors of the speaking circuits. Prior to this invention, no method has been outlined for determining the values and mode of connection of these nine balancing condensers in a practical case. A novel mathematical procedure has, therefore, been worked out for determining directly from the nine measured capacitative couplings the values of the nine capacities required for balancing the same. This mathematical process, therefore, constitutes an essential part of the present invention.

Having outlined in a preliminary way above the problem involved, the balancing procedure will now be explained in detail with the aid of the drawings, in which Figure 1 shows schematically a pair of quads in a cable with the sixteen part capacities between the conductors of the one and of the other quad indicated. Fig. 2 shows a diagram of two speaking circuits with the part capacities between the conductors of the one and the other indicated. Fig. 3 shows the quads of Fig. 1 with the part capacities C_1 to C_{16} not shown, and with certain balancing capacities indicated. Fig. 4 shows a chart used in mathematical determination of the balancing capacities. Fig. 5 gives a chart in which a numerical example illustrating the determination of the

balancing capacities in a specific case is worked out.

In Fig. 1, conductors 1, 2, 3 and 4 constitute one quad of the cable while conductors 5, 6, 7 and 8 constitute a second quad therein. In the first quad, the side circuits are indicated by A_1 and A_2 , respectively, while the phantom is indicated by A . In the second quad, the corresponding designations are B_1 , B_2 and B . The capacities C_1 to C_{16} , inclusive, show all possible part capacities between the conductors of the first quad and the conductors of the second quad. By connecting in parallel with each part capacity C a fixed capacity X such that

$$C_1 + X_1 = C_2 + X_2 = \dots = C_{16} + X_{16}, \quad (1)$$

the inter-quad couplings between the speaking circuits will be balanced up so that circuits A , A_1 and A_2 will have no reaction on B , B_1 and B_2 or vice versa.

The truth of the above statement can be demonstrated by reference to Fig. 2 in which conductors AB represent one speaking circuit and conductors CD the second. The inherent part capacities between the conductors of one and the other speaking circuits are indicated by n_1 to n_4 , respectively. If a voltage is impressed between conductors CD , in order that no effect be produced on circuit AB as a result thereof, it is necessary that the following relation exist between the part capacities:

$$\frac{n_1}{n_2} = \frac{n_3}{n_4} \quad (2)$$

In other words, under the assumption of Equation (2), the arrangement constitutes a balanced bridge of which the capacities n_1 to n_4 , inclusive, are the balancing arms and conductors AB the equipotential points.

If the relation between the part capacities is not such as to furnish the equality represented by Equation (2) then a balance can be obtained by connecting in parallel with each part capacity n a fixed capacity x , such that

$$n_1 + x_1 = n_2 + x_2 = n_3 + x_3 = n_4 + x_4. \quad (3)$$

Under the conditions of Equation (3), the bridge, of course, becomes balanced, since all the balancing arms contain a like impedance. It is not necessary, however, to use four capacities for balancing up the bridge. Referring to Equation (2), if the ratio on the left side of the equation does not equal that on the right, it can be made the same by connecting in shunt with one of the capacities n a single capacity x of proper value to reduce the equation to an equality.

Thus, referring now to Fig. 3 which shows sections of the quads A and B of Fig. 1, with the capacities C_1 to C_{16} not indicated, each side circuit to side circuit coupling can be balanced up, using the last method discussed above, by connecting only a single condenser

between a conductor of one and the other side circuit. As an illustration of this, Fig. 3^a shows the balancing of the coupling between side circuits A_1 and B_1 by means of the single capacity t_1 . The other side to side couplings A_1B_2 , A_2B_1 and A_2B_2 can correspondingly be balanced up by suitably connecting a single condenser in each case.

In balancing up the side circuit to phantom circuit couplings by this procedure, it should be remembered, of course, referring to Fig. 2, that if AB represents the side circuit and CD the phantom, then circles C and D each represent the two conductors constituting the lead and return path of the phantom circuit and the capacities n_1 to n_4 , inclusive, each represent the two part capacities from a conductor of the side circuit to the two conductors comprising the lead or return path of the phantom circuit. In the same manner, in determining the phantom to phantom couplings, each circle A to D represents the two conductors constituting the lead or return path of a phantom circuit and each capacity n is the sum of the four-part capacities between such pairs of conductors.

In balancing up a side to phantom coupling, two additional capacities are required in order not to disturb the previously balanced side to side circuit couplings. The manner of connecting these two condensers is indicated in Fig. 3^b by condensers t_2 to t_3 which balance the side to phantom coupling A_1B . There are three other side to phantom couplings which require balancing by the same procedure, namely, A_2B , B_1A and B_2A . In order to balance up the phantom to phantom coupling AB , four capacities are required in order not to disturb the previously balanced side to side and side to phantom couplings. In Fig. 3^c, condensers t_4 to t_7 indicate the mode of connecting the balancing capacities for this case. The method outlined immediately above describes the known procedure for balancing up the inter-quad capacitative couplings. It will be seen that the method requires a total of sixteen capacities. The method is cumbersome in that the side to side couplings must be measured and corrected before measurements can be made on the side to phantom couplings, since the balancing up of the former effects the latter. Similarly, the side to phantom couplings must be measured and corrected before the

phantom to phantom coupling can be attacked. It is thus apparent that the known method of balancing the couplings is not only long and tedious but requires the maximum number of balancing capacities. Furthermore, where such procedure is followed on a large scale, it requires maintaining in stock a supply of condensers manufactured in groups of one, two and four units each for balancing the side to side, side to phantom and phantom to phantom couplings, respectively. With the method of the present disclosure, however, it would be required to maintain in stock only the single unit elements.

Coming, now, to a discussion of the present disclosure and referring to Fig. 2, the capacitative coupling between the circuits AB and CD may be calculated according to the following equation:

$$k = n_1 - n_2 - n_3 + n_4 \quad (4)$$

The above equation is approximately true on the assumption that the deviation of the capacities n from the average value is small in comparison with the average value. The equation itself is derivable from a consideration of the balanced bridge arrangement of the capacities n_1 to n_4 , inclusive. Now, in order that the coupling capacity k of Equation (4) disappear, the inherent part capacities should each receive an addition x , such that k becomes zero, i. e.,

$$0 = (n_1 + x_1) - (n_2 + x_2) - (n_3 + x_3) + (n_4 + x_4) \quad (5)$$

from which of course, it is obvious that

$$x_1 - x_2 - x_3 + x_4 = -k \quad (6)$$

In other words the equation for the additions x has the same form as that for the part capacities n but with the sign of k reversed.

The general Equation (6) can be applied to the nine couplings between the speaking circuits of quads A and B of Fig. 1, remembering, of course, that wherever a phantom circuit is involved, two or four part capacities must replace certain of the single capacities of Equation (6). Keeping this point in mind, the additions required for removing the nine couplings between the speaking circuits of Fig. 1 must comply with the following nine equations (a) to (i), inclusive:

Table I

Equation	Circuit coupling	
a	A/B	$-k_1 = +x_1 + x_2 + x_3 + x_4 - x_5 - x_6 - x_7 - x_8 - x_9 - x_{10} - x_{11} - x_{12} + x_{13} + x_{14} + x_{15} + x_{16}$
b	A ₁ /B	$-k_2 = +x_1 + x_2 - x_3 - x_4 - x_5 - x_6 + x_7 + x_8$
c	A ₂ /B	$-k_3 = -x_9 + x_{10} - x_{11} - x_{12} - x_{13} - x_{14} + x_{15} + x_{16}$
d	B ₁ /A	$-k_4 = +x_1 - x_2 + x_3 - x_4$
e	B ₂ /A	$-k_5 = +x_5 - x_6 - x_7 + x_8$
f	A ₁ /B ₁	$-k_6 = -x_{13} + x_{14} - x_{15} + x_{16}$
g	A ₁ /B ₂	$-k_7 = +x_5 - x_6 - x_7 + x_8$
h	A ₂ /B ₁	$-k_8 = +x_9 - x_{10} - x_{11} + x_{12}$
i	A ₂ /B ₂	$-k_9 = +x_{13} - x_{14} - x_{15} + x_{16}$

The values x_1 to x_{16} , inclusive, are the additions to part capacities C_1 to C_{16} , respectively, of Fig. 1 required for removing the couplings.

It will be noted that the group of equations in Table I comprise sixteen unknown quantities with only nine equations for evaluating the same. The problem, therefore, cannot be solved uniquely. Arbitrary values can be assigned to any seven of the variables and the equations solved uniquely for the remaining nine roots. Practically, of course, seven of the variables would be set equal to zero, since physically this would correspond to omitting the connection of balancing condensers between the corresponding conductors. Now, there are ${}_{16}C_7 = 11,440$ different combinations of the variables x having seven values set equal to zero. Of these 11,440 combinations, however, all are not available in a practical solution of the problem, since in addition to the first restriction that seven of the roots become zero, there is a second restriction that the remaining nine roots must all be positive. Physically, the necessity for this second restriction lies in the fact that capacities can only be added between conductors and none taken away in balancing up the couplings.

There is no simple way of predicting, for a given set of measured coupling values, which of the above combinations will produce nine positive roots in addition to the seven zero values. This is due to the fact that whether roots work out positive or negative depends upon the sign of the measured coupling values and also upon their relative magnitudes. Now, there are something like 2×10^8 different ways of arranging the values k , according to their relative magnitudes also taking into account the possible sign combinations. Since any given measured set of coupling values might be any one of these possible arrangements, it is readily apprehended that it is almost impossible to predict what combinations of seven values of the variables set equal to zero will produce nine positive roots in a given case.

For a given set of measured coupling values, one might, of course, proceed to select at random successive combinations of seven variables set equal to zero and solve the equations simultaneously for the remaining nine, until by chance, a combination was found producing nine positive roots. The work involved in such procedure, however, would soon become prohibitive if the first few guesses were wrong.

It, therefore, becomes necessary to devise some fairly simple method whereby a solution may be obtained in a given case producing nine positive and seven zero roots. Such a method constitutes an essential part of the present invention and consists in assuming suitable solutions for the nine equations of Table I individually, combining these solu-

tions for the individual equations in such manner as to obtain a general solution for all nine of the equations, and then applying to the general solution certain alterations which are ineffective as to the individual equations, until seven values are reduced to zero and leaving nine positive values. 70

The equations of Table I are set forth in a somewhat different form on the chart of Fig. 4. Since the signs of the variables x_1 to x_{16} is the important feature here, the variable designations x_1 to x_{16} are placed in the upper row of squares on the chart. In the squares below the x 's are placed the signs thereof, in accordance with their occurrence in Equations (a) to (i), inclusive, of Table I. The equation designation is indicated in column 1, while column 2 indicates the circuit coupling designation and column 3 gives the coupling constant k . It is important to point out at this point that in measuring the coupling k , between any two speaking circuits, the measured value k may be plus or minus and that in Equations (a) to (i) inclusive, minus the measured value of k including its sign, is taken. 80

Referring now to Fig. 4, assume a solution for Equation (a) by apportioning the measured value of the coupling constant equally among the variables of opposite sign thereto, the remaining variables, for the moment, being assumed zero. Thus, for example, if the measured value k_1 is positive, the solution of Equation (a) is assumed in the form 95

$$x_5 = x_6 = \dots = x_{11} = x_{12} = \frac{k_1}{8} \quad (7)$$

with x_1 to x_4 and x_{13} to x_{16} taken as zero. If, now, the values of the variables assumed for the solution of Equation (a) are substituted in Equations (b) to (i), inclusive, respectively, it will be noted that in each case they produce zero resultant effect on such equations, owing to the sequence of the signs of the variables in such equations. For example, if 105

the value $\frac{k_1}{8}$ be substituted in Equation (b) for the variables x_5 to x_{12} , the effect will be zero, since x_5 and x_6 are negative, while x_7 and x_8 are positive. The values x_9 to x_{12} , of course, do not affect Equation (b), since they are not present therein. The same result would be obtained by applying the assumed solution of Equation (a) to any of the Equations (b) to (i), inclusive. Thus the assumed solution, while valid for Equation (a), has zero resultant effect upon Equations (b) to (i), inclusive. The same result would follow had the measured value of k_1 been negative, requiring the assignment of the value $\frac{k_1}{8}$ to the positive variables x_1 to x_4 and x_{13} to x_{16} , inclusive, of Equation (a) in order to establish an equality. 110 120 125 130

Having assumed the solution for Equation (a) which has no resultant effect on the remaining equations, a solution will now be assumed for Equation (b) which has no reaction on Equations (a) and (c) to (i), inclusive. Assume for the moment that the measured value of k_2 is positive and, consequently, apportion k_2 equally among the negative values of x in Equation (b), giving

$$10 \quad x_3 = x_4 = x_5 = x_6 = \frac{k_2}{4} \quad (8)$$

The other variables x of Equation (b) are, for the moment, assumed equal to zero. The assumed solution for Equation (b), it will be noted from an inspection of the signs of Fig. 4, has zero resultant effect upon the remaining Equations (a) and (c) to (i), inclusive.

20 Thus, inserting the value $\frac{k_2}{4}$ for the variables x_3 to x_6 in Equation (a), it will be seen that the total effect is zero, since x_3 and x_4 are positive while x_5 and x_6 are negative in such equation. A similar result will likewise be obtained for Equations (c) to (i), inclusive. Also, if the measured value of k_2 were negative instead of positive the same result would 25 follow by assigning the value $\frac{k_2}{4}$ to the variables x_1 , x_2 , x_7 , and x_8 .

Thus, individual solutions have been obtained for Equations (a) and (b) which have no reactive effect upon the remaining equations. In a similar manner a solution for Equation (c) is assumed by assigning the value $\frac{k_3}{4}$ to the variables of opposite sign thereto in such equation, and likewise, in Equation (d) a solution is obtained by assigning the value $\frac{k_4}{4}$ to the variables of opposite sign thereto, and in Equation (e) assigning the value $\frac{k_5}{4}$ to the variables of opposite sign thereto.

Coming now to Equation (f), if a value $\frac{k_6}{2}$ is assigned to the variables of opposite sign, an inspection of Fig. 4 will show that the solution thus assumed, while producing zero resultant effect upon Equations (b) to (e) and (g) to (i), inclusive, will produce a coupling effect when the values are substituted in Equation (a). For example, if the measured value k_6 is negative, the value $\frac{k_6}{2}$ is assigned to the variables x_1 and x_4 in Equation (f). Substituting these values in Equation (a) gives a total resultant effect equal to k_6 , since both x_1 and x_4 are positive in Equation (a). In order, therefore, to off- 65 set the effect of the assumed solution for

Equation (f) on Equation (a), in addition to assigning the value $\frac{k_6}{4}$ is also assigned to the variables x_5 to x_8 , inclusive, or to the variables x_9 to x_{12} . Thus, for example, with the measured value of k_6 negative, the value $\frac{k_6}{2}$ is assigned to the variables x_1 and x_4 and

the value $\frac{k_6}{4}$ is assigned to the variables x_5 75

to x_8 , inclusive, for example, by placing such values in the proper squares of a chart similar to Fig. 4. If these values of the variables are substituted in Equation (a), the total resultant effect will be zero, since $x_1 + x_4 = +k_6$, and $-x_5 - x_6 - x_7 - x_8 = -k_6$, or $k_6 - k_6 = 0$.

80 The assignment of the value $\frac{k_6}{4}$ to the variables x_5 to x_8 , inclusive, has no effect on the solution of Equation (f) since these variables do not appear in that equation. Had the measured value k_6 been positive, the solution of Equation (f) would be obtained by as- 85 signing the value $\frac{k_6}{2}$ to the variables x_2 and

90 x_3 and the value $\frac{k_6}{4}$ to the variables x_5 to x_8 , or x_9 to x_{12} . An inspection of the other equations will show that the complete assumed solution for Equation (f) likewise has zero resultant effect on such equations.

95 For Equation (g), a solution is obtained for positive k_7 by assigning $\frac{k_7}{2}$ to x_6 and x_7 and

100 in addition assigning $\frac{k_7}{4}$ to x_1 to x_4 , or x_{13} to x_{16} , inclusive. For negative k_7 the value $\frac{k_7}{2}$ is assigned to x_5 and x_8 and the value $\frac{k_7}{4}$ to the variables x_1 to x_4 , or x_{13} to x_{16} , inclusive, to offset the coupling effect of the assumed 110 solution for Equation (g) on Equation (a).

Likewise, in Equation (h), the value $\frac{k_8}{2}$ is assigned to the variables of opposite sign, 115 and to offset the coupling effect on Equation

(a) in addition the value $\frac{k_8}{4}$ is assigned to the variables x_1 to x_4 or x_{13} to x_{16} , inclusive.

120 For Equation (i), the value $\frac{k_9}{2}$ is assigned to the variables of opposite sign, and to offset the coupling effect on Equation (a) the value $\frac{k_9}{4}$ is assigned to x_5 to x_8 or x_9 to x_{12} , inclusive.

125 Suppose, now, that the values assigned to the variables in the solution of the individual equations were inserted in the proper squares of a chart similar to Fig. 4 and the columns

- added vertically. Thus, certain squares in Equation (a) would contain the value $\frac{k_1}{8}$, and in Equation (b) certain squares would contain the value $\frac{k_2}{4}$, etc. The columns x_1 to x_{16} , inclusive, when summed up vertically, would thus give a set of resultant values constituting a single value for each variable x , and set of resultant values would have the peculiar property that it would satisfy all of the Equations (a) to (i), inclusive. That this must be the case follows from the manner in which the resultant set of values was obtained, i. e., by summing up nine sets of individual values each of which constituted a solution of one of the Equations (a) to (i), inclusive, but which had zero resultant effect on all of the other equations.
- 20 The set of values obtained in this manner constituting a general solution for the nine coupling equations, will, owing to the manner in which it was obtained, as a general rule, comprise sixteen positive values. Thus far, therefore, it is not a solution of the type desired since, as was explained above, the desired solution must contain nine positive roots and seven zero roots. The next problem, therefore, is to alter the general solution in such manner that seven of the variables will be reduced to zero, leaving only nine positive values. This alteration must be accomplished in such manner that the general solution finally obtained will individually satisfy all of the nine Equations (a) to (i), inclusive.
- Now, it can be shown, with the aid of Fig. 4, that certain order changes may be applied to the general solution without affecting its validity as a solution of the nine equations.
- 40 For example, the values of the variables x_1 to x_8 , inclusive, in the general solution, might be simultaneously altered by the same amount without affecting the validity of the general solution. This is due to the fact that, owing to the arrangement of the signs of the variables x_1 to x_8 , inclusive, in the nine equations, the same change applied to all such variables would add up to zero in each equation. Thus, if the value p were added to these variables, the effect on Equation (a) would be $4_p - 4_p = 0$, since x_1 to x_4 are positive while x_5 to x_8 are negative. Similarly, in Equation (b), x_1, x_2, x_7 and x_8 are positive while x_3 to x_6 are negative, and so on for all the remaining equations.
- Having thus demonstrated how one alteration may be applied to the general solution without affecting its validity as a solution of the nine equations, a table will now be included showing the possible changes of this type. Without affecting the coupling equations, the following variables may be simultaneously increased or diminished by the same amount.

Table II

(c ₃)	Values 1 and 2 in Groups III and IV	75
(c ₄)	Values 3 and 4 in Groups III and IV	
(c ₅)	Values 1 and 3 in Groups I and III	
(c ₆)	Values 2 and 4 in Groups I and III	
(c ₇)	Values 1 and 3 in Groups II and IV	
(c ₈)	Values 2 and 4 in Groups II and IV	80

In Table II, the groups refer to the groupings of Fig. 4. The first column is merely a code designation for the particular alteration in question. Thus, alteration c_3 means that the first and second variables x of Groups III and IV of Fig. 4 are to be altered simultaneously by the same amount.

By properly applying certain of the alterations specified in Table II to the general solution, it is possible to successively reduce certain of the variables x to zero. This process is continued until finally seven such values are so reduced, leaving only nine positive roots. The procedure, of course, is to apply an alteration in accordance with Table I, which will first reduce the smallest root in the general solution to zero. Thus, suppose the smallest root is $x_{14} = d$. This root could be reduced to zero without affecting the validity of the general solution by adding $-d$ to the general solution in accordance with the alterations a, b_3, b_4, c_3 or c_8 of Table II, whichever such alterations seem best adapted in the particular case. Having thus reduced the smallest root to zero in this manner, the smallest of the values remaining after such alteration is next reduced to zero in a similar manner, and so on.

In applying the method outlined above to specific problems it has been found that in some instances it is difficult to reduce as many as seven of the variables to zero owing to the restrictions as to the types of alterations which can be applied in accordance with Table II. For this reason a slight modification of the method described above will now be outlined by means of which latter method it is always possible to reduce seven of the variables to zero, leaving nine positive values. This latter method will be illustrated with a numerical example, which will also furnish a definite picture as to the manner in which the general process is applied.

Referring again to Fig. 4, it was demonstrated above that in general the apportionment of a given coupling constant equally among the variables of opposite sign thereto constitutes a solution for the corresponding coupling equation but which is ineffective as applied to the other equation. Now, it is not

necessary to apportion the coupling constant k equally among all the variables of opposite sign to accomplish this result. For example, referring to Fig. 4, assume a solution

5 for Equation (a) by assigning the value $\frac{k_1}{4}$

to the variables x_1 to x_4 , inclusive, if k_1 is negative, or x_5 to x_8 , inclusive, if k_1 is positive. This restricts the assignment of values

10 of k to Groups I and II, leaving Groups III and IV of Fig. 4 free from the assignment

15 of values. Now a glance at the signs of the variables x_1 to x_8 in Equations (b) to (i), inclusive, will show that the assumed solution

15 for Equation (a) produces zero resultant effect on all the remaining equations. In Equa-

tion (b) the assumed solution will be $\frac{k_2}{2}$ ap-

20 portioned equally among the variables of op-

posite sign thereto in Group I only. Such a solution, while producing zero effect on Equa-

25 tions (c) to (i), inclusive, will produce a cou-

pling effect on Equation (a) since the vari-

ables x_1 to x_4 all have the same sign in such

equation. To offset the effect on Equation

(a), therefore, in addition to assigning the

value $\frac{k_2}{2}$ to the variables in Group I of op-

30 posite sign, the value $\frac{k_2}{4}$ is also assigned to

the variables x_5 to x_8 , inclusive, of Group II.

In Equation (c), the assumed solution is

35 $\frac{k_3}{2}$ assigned to the variables of opposite sign

in Group III and to offset the coupling ef-

fect on Equation (a) the value $\frac{k_3}{4}$ is also

40 apportioned among the variables x_1 to x_4 ,

inclusive. In Equation (d), $\frac{k_4}{2}$ is assigned

to the variables of opposite sign in Group I

and in addition $\frac{k_4}{4}$ to the variables x_5 to x_8 ,

45 inclusive, in Group II. In Equation (e),

the assumed solution is $\frac{k_5}{2}$ assigned to the

variables of opposite sign in Group II and

50 in addition $\frac{k_5}{4}$ is assigned to the variables

x_1 to x_4 , inclusive, in Group I. In Equation

(f), the solution is $\frac{k_6}{2}$ assigned to the vari-

55 ables of opposite sign in Group I and $\frac{k_6}{4}$ to

the variables x_5 to x_8 in Group II. In Equa-

tion (g), the solution is $\frac{k_7}{2}$ assigned to the

60 variables of opposite sign in Group II and

$\frac{k_7}{4}$ to x_1 to x_4 , inclusive, in Group I. In Equa-

65 tion (h), $\frac{k_8}{2}$ is assigned to the variables of

opposite sign in Group III and $\frac{k_8}{4}$ to the variables x_1 to x_4 , inclusive, in Group I. In Equation (i), $\frac{k_9}{2}$ to the variables of opposite

70 sign in Group IV and $\frac{k_9}{4}$ to the variables x_5 to x_8 , inclusive, in Group II.

Following the rules outlined immediately above, it will be found that the individual solution assumed for each of the nine Equations (a) to (i), inclusive, has zero resultant effect on any of the other equations. Furthermore, with the exception of Equations (c), (h) and (i), the values assigned to the variables are limited to Groups I and II of Fig. 4, leaving Groups III and IV relatively free from such assignments. The advantage of this arrangement, as will now be pointed out by the numerical example, lies in the fact that, irrespective of the signs of the measured coupling constants k , at least three of the variables will be initially zero in the general solution, thus requiring the reduction to zero of only four variables by the methods outlined above.

Referring now to Fig. 5, which shows the application of the latter method to a specific example, column 1 of the chart shows the coupling designations in accordance with Fig. 1. Column 2 gives the coupling designations, as k_1 , k_2 , etc. Column 3 gives the measured coupling values in an actual case, together with the sign thereof. Thus, the measured coupling constant k_1 was +100, k_2 +80, etc. The upper portion of the squares in column 3 are marked negative and the lower portion positive, and the measured coupling value is in each case written in opposite its proper sign. In Groups I to IV, inclusive the shaded portions under the variables x_1 to x_{16} block out the x 's of the same sign as the measured coupling value, since the coupling value is never apportioned among such variables. For example, referring to the coupling A/B, the measured coupling is +100, and since the variables x_1 to x_4 are positive the lower portions of the squares are blocked out, preventing the apportionment of the coupling among such variables, while the lower portion of the squares corresponding to x_5 to x_8 , inclusive, are left free, permitting the apportionment of the coupling constant among them since the signs of these variables are negative.

For the coupling A/B the value $\frac{k_1}{4} = 25$ is assigned to the variables x_5 to x_8 since the measured value of k_1 is positive. It might be well to refer to the chart of Fig. 4 in connection with the signs of the variables here.

For the coupling A₁/B the value $\frac{k_2}{2} = 40$ is assigned to the variables x_3 and x_4 since k_2

120

125

130

is positive, and to offset the coupling effect on Equation (a) the value $\frac{k_2}{4} = 20$ is assigned to the variables x_5 to x_8 , inclusive. In the same manner, following down the entire series of values, the measured coupling value is apportioned equally among the variables of opposite sign in accordance with the rules outlined above, and to prevent a coupling effect on Equation (a) an additional apportionment of $\frac{k}{4}$ is assigned to all the variables of Group I or Group II, as the case may be, to offset the coupling effect on Equation (a).

Having written in the solutions for the individual equations in the manner described, the various x columns are now added vertically, giving the general solution indicated by line T of the chart. It will be noted in the general solution thus obtained that three of the roots are initially zero, namely, x_{12} , x_{14} , and x_{15} . This is due, of course, to the modified method which was outlined restricting the assignment of values to the variables in Groups III and IV. An inspection of the chart will show that, irrespective of the signs of the measured coupling constants, three of the roots in Groups III and IV will always be initially zero in the general solution.

The final step in the solution consists in altering the general solution of line T in such manner as to reduce four additional roots to zero. The necessary alterations, of course, are made in accordance with Table II above.

The steps are as follows:

1. In Groups I and III of Fig. 5, apply the alteration c_5 or c_6 of Table II to the zero value in Group III so that $x_9 = x_{10}$ or $x_{11} = x_{12}$, as the case may be. Thus, in the example given, apply the alteration c_6 of Table II by adding the value +2 to x_2 , x_4 , x_{10} and x_{12} . The code designation of the alteration applied is indicated in column 3 of Fig. 5 under T. The upper portion of c_6 shows the alteration applied while the lower portion of c_6 shows the value of the variable altered after such modification. Thus, in the example, after modification $x_{12} = x_{11} = 2$.

2. Next, apply the alteration c_3 or c_4 of Table II so that the smaller of the values x_{11} and x_{12} or x_9 and x_{10} , as the case may be, by addition becomes equal to the other two values already equal, or vice versa. In case the two equal values are the smallest in Group III these two smallest values are made equal to the smaller value of the remaining two values in the group. Thus, in the example, line c_6 , x_{11} and x_{12} are now equal to 2, which is smaller than either $x_9 = 20$ or $x_{10} = 24$. Consequently, apply the alteration c_4 of Table II by adding the value +18 to the variables x_{11} , x_{12} , x_{15} and x_{16} . This alteration, line c_4 of Fig. 5, makes $x_9 = x_{11} = x_{12} = 20$, as shown.

3. Apply the alterations c_7 or c_8 so that the smallest number in Group IV becomes equal

to zero. In the example, the smallest number in Group IV is $x_{18} = 14$. Hence, applying the alteration c_7 , add -14 to x_5 , x_7 , x_{13} and x_{15} . This reduces x_{18} to zero, see line c_7 , Fig. 5.

4. Apply the alteration b_2 of Table II so that the three equal values in Group III become zero. Hence, in the example, line b_2 Fig. 5, add -20 to the variables x_1 to x_4 , inclusive, and x_9 to x_{12} , inclusive, thus reducing x_9 , x_{11} and x_{12} to zero.

5. Apply the alteration b_1 of Table II so that the smallest value of Groups I and II become zero. Thus, in the example, $x_2 = 32$ is now the smallest value in Groups I and II. Hence, line b_1 , Fig. 5, add -32 to x_1 to x_8 , inclusive, in accordance with alteration b_1 , Table II, thus reducing x_2 to zero.

6. Apply the alteration c_1 or c_2 so that the smallest remaining value in Groups I and II becomes zero. Thus, in the example, apply the alteration c_2 , Table II, by adding -22 to x_3 , x_4 , x_7 and x_8 , thus reducing x_4 to zero, line c_2 , Fig. 5.

The bottom line of c_2 , Fig. 5, now gives the solution required consisting of nine positive values and seven zero values of the variables x_1 to x_{16} , inclusive. This set of values satisfies all the nine Equations (a) to (i), inclusive, and hence if the capacities x_1 to x_{16} of line c_2 , Fig. 5, are connected in parallel with the corresponding quad capacities c_1 to c_{16} , respectively, of Fig. 1, the couplings k_1 to k_9 will be completely balanced so that the talking circuits at quad A will have no interfering effect on those at quad B, or vice versa.

The final solution of line c_2 , Fig. 5, is, of course, but one of many possible solutions. For example, starting with the values of line T, a different set of variables might have been reduced to zero by the general methods outlined. Or initially, the values of k might have been apportioned as much as possible among Groups III and IV, or I and III, or II and IV, instead of between Groups I and II, as was done in the example shown. According to the particular groups thus stressed different final solutions would be obtained. Solutions of the problem are not included herein showing the exact procedure when the coupling apportionments are limited to the group pairs other than Groups I and II for the reason that the solution illustrated, shows sufficiently well the general line of attack.

In dealing with long cable circuits, it may be necessary to balance up the inter-quad couplings at a number of points. For example, in loaded cable circuits, it might be advisable to balance the inter-quad couplings in each loading section. In such case, it is recommended to change the scheme of solution employed in regular succession from balancing point to balancing point, in order that the nine balancing capacities will not be connected between the same conductors at each such point. That is, if the scheme of solution

at the first balancing point consists in limiting the coupling apportionments to Groups I and II, then at the second point, the coupling apportionments should be limited to groups say II and IV, and at the next point, to Groups I and III, and so on, using all the combinations over and over again in regular succession.

In the claims: The capacities x_1 to x_{16} of Equations (a) to (i) inclusive of Table I, will be referred to as the "balancing capacities" which in fact they are. The phantom to phantom circuit coupling Equation (a) of Table I will, for the sake of brevity, be referred to by the term "phantom equation". Likewise, the phantom circuit to side circuit coupling Equations (b) to (e) inclusive of Table I will be termed the "phantom-side equations", while the term "side circuit equations" will be utilized to designate the side circuit to side circuit coupling Equations (f) to (i) inclusive. By "successive balancing capacities" will be meant the values x_1 , x_2 etc., occurring in the order shown by the equations of Table I above.

What we claim as new and desire to secure by Letters Patent of the United States is:

1. Method for balancing the couplings between adjacent quads, especially in telephone cables, which consists in measuring the inter-quad couplings between the transmission circuits of the one and of the other quad, calculating from such measured couplings directly the values of the nine capacities for balancing the same, suitably connecting between the conductors of the one and of the other quad, nine such capacities whereby the inter-quad couplings are simultaneously made to disappear.

2. Method for balancing the couplings between adjacent quads, especially in telephone cables, which consists in measuring the inter-quad couplings between the transmission circuits of the one and of the other quad, apportioning the measured couplings values equally among the balancing capacities of opposite sign thereto in their respective coupling equations, rendering such apportionments in the side circuit equations ineffective as applied to the phantom equation by further apportioning the couplings in the respective side circuit equations equally among four successive capacities of proper sign not occurring therein, summing up the values thus assigned the respective balancing capacities, successively altering through changes ineffective as to the individual equations the set of resultant sums through like changes simultaneously applied to certain groups thereof, until finally seven of the sixteen possible sums are reduced to zero while the remaining nine assume positive values, properly connecting between the conductors of the one and of the other quad nine capacities corresponding to said nine positive values,

whereby all the aforesaid inter-quad couplings are simultaneously made to disappear.

3. Method for balancing the couplings between adjacent quads, especially in telephone cables, which consists in measuring the inter-quad couplings between the transmission circuits of the one and of the other quad, apportioning the measured couplings equally among the balancing capacities of opposite sign thereto in their respective coupling equations, limiting such apportionment in advance except for the equations having no capacities therein, to two groups of four successive capacities, each said group having opposite signs in the phantom equation, rendering such apportionments in the other equations ineffective as applied to the phantom equation by further apportioning the couplings in such other equations equally among the capacities in one group aforesaid of proper sign, summing up the values thus assigned the respective balancing capacities, successively altering through changes ineffective as to the individual equations the set of resultant sums through like changes simultaneously applied to certain groups thereof, until finally seven of the sixteen possible sums are reduced to zero while the remaining nine assume positive values, properly connecting between the conductors of the one and of the other quad, nine capacities corresponding to said nine positive values,

4. Method for balancing the couplings between adjacent quads, especially in telephone cable, which consists in measuring the inter-quad couplings between the transmission circuits of the one and of the other quad, apportioning the measured couplings equally among the balancing capacities of opposite sign thereto in their respective coupling equations, limiting such apportionment in advance except for the equations having no capacities therein, to two groups of four successive capacities each, having opposite signs in the phantom equation, rendering such apportionments in the other equations ineffective as applied to the phantom equation by further apportioning the couplings in such other equation equally among the capacities in one group aforesaid of proper sign, summing up the values thus assigned the respective balancing capacities, successively altering through changes ineffective as to the individual equations the set of resultant sums through like changes simultaneously applied to certain groups thereof, until at first five sums in the two non-limited groups and finally two additional sums in the aforesaid limited groups are reduced to zero while the remaining nine of the sixteen possible sums assume positive values, properly connecting between the conductors of the one and the other quad, nine capacities corresponding to

said nine positive values whereby all the aforesaid inter-quad couplings are simultaneously made to disappear.

5. Method for balancing at a plurality of successive balancing points the couplings between adjacent quads, especially in telephone cables, which consists for each balancing point, in measuring the inter-quad couplings between the transmission circuits of the one and of the other quad, apportioning the measured couplings equally among the balancing capacities of proper sign in their respective coupling equations, limiting such apportionment in advance where possible, to 10 two groups of four successive balancing capacities, each said group having opposite signs in the phantom equation, rendering such apportionments in the other equations ineffective as applied to the phantom equation by 15 further apportioning the couplings therein 20 equally among the capacities in one group aforesaid of proper sign, summing up the values thus assigned the respective balancing capacities, successively altering through 25 changes ineffective as to the individual equations the set of resultant sums, until seven of the possible sixteen are reduced to zero while the remaining nine assume positive values, 30 properly connecting between the conductors of the one and of the other quad at the balancing point in question, nine capacities corresponding to said nine positive values whereby the inter-quad couplings at such balancing point are simultaneously made to disappear, 35 changing preferably in regular succession from balancing point to balancing point the combination of two groups aforesaid to which the apportioned values are limited.

In witness whereof, we have hereunto set 40 our hands this 15th day of November, 1928.
